UNITED STATES PATENT OFFICE.

PANAYIOTIS PANOULIAS, OF NEW YORK, N. Y.

DIPPING-FRAME FOR COATING CANDIES.

No. 809,737

Specification of Letters Patent.

Patented Jan. 9, 1906.

Application filed May 6, 1905. Serial No. 259,114.

To all whom it may concern:

Be it known that I, PANAYIOTIS PANOULIAS, a subject of the King of Greece, residing at New York, in the county of New York and State of New York, have invented certain new and useful Improvements in Dipping-Frames for Coating Candies, of which the following is a specification, such as will enable those skilled in the art to which it appertains to make and use the same.

This invention relates to dipping-frames for use in coating candies, and more particularly chocolates, such as is shown and described in United States Letters Patent No. 1,663,359, granted to me December 4, 1900; and the object thereof is to provide an improved dipping-frame of this class by means of which the candies or cores thereof may be immersed in liquid chocolate or other material, so as to coat the same, a further object being to provide a dipping-frame of the class described with improved devices whereby the coated candies are marked to simulate the formation of hand-dipped candies, a further object being to provide a dipping-frame of the class described adapted for either manual or mechanical operation or agitation; and with these and other objects in view the invention consists in a dipping-frame of the class specified constructed as hereinafter described and claimed.

The invention is fully disclosed in the following specification, of which the accompanying drawings form a part, in which the separate parts of my improvement are designated by suitable reference characters in each of the views, and in which—

Figure 1 is a plan view of my improved dipping-frame; Fig. 2, a front view thereof; Fig. 3, an end view looking in the direction of the arrow *x* of Fig. 1; Fig. 4, a transverse section on the line 4 4 of Fig. 2; Fig. 5, a transverse section on the line 5 5 of Fig. 2; Fig. 6, a view similar to Fig. 5, but showing the parts in a different position; and Fig. 7, a sectional end view of a combination casing and table or support in connection with which in practice my improved dipping-frame is used.

In the construction of my improved dipping-frame I provide two end plates or members *a*, rigidly connected by horizontal and parallel rods *b* and *b*², connected with the back lower and back upper part of said end plates or members, and each of said end plates or members is provided in the bottom

portion thereof with a horizontal slot or opening *a*³ and with a forwardly-directed portion or arm *a*⁴, in the bottom part of which is formed a slot or opening *a*⁵, which ranges forwardly and backwardly and the rear end portion of which is curved downwardly and provided with a downwardly-directed extension *a*⁶.

Mounted in the top back portion of the frame plates or members *a* is a rotatable rod *b*³, provided at one end (the right-hand end, as shown in the drawings) with a collar *c*, having a forwardly-directed arm *c*², an upwardly and backwardly directed arm *c*³, and a backwardly and downwardly directed arm *c*⁴, and said rod is provided at the opposite end thereof with a collar *d*, having a forwardly-directed arm *d*² and a backwardly and downwardly directed arm *d*³.

Mounted in the bottom horizontal slots or openings *a*³ in the end plates or members *a* and movable forwardly and backwardly therein is a bar *e*, having a plurality of equally-spaced and forwardly-directed pins or needles *e*², and mounted in the bottom portions of the end plates or members *a*, under the slots or openings *a*³, is a rotatable rod *e*³, to one end of which—the right-hand end as shown in the drawings—is secured an arm *f*, that part of which adjacent to the rod *e*³ is widened and provided with an L-shaped slot or opening *f*², and the corresponding end of the bar *e* passes through said slot or opening, as clearly shown, and pivoted to the arm *f*, above the slot or opening *f*², is a link member *f*³, having a longitudinal slot *f*⁴, through which is passed a headed screw, pin, or similar device, which is rigidly secured to the upwardly and backwardly directed arm *c*³ of the collar *c* on the rotatable rod *b*³. The opposite end of the rotatable rod *e*³—the left-hand end in the construction shown—is provided with a backwardly and upwardly directed arm *g*, which is of exactly the same shape as that part of the arm *f* in which the L-shaped slot or opening *f*² is formed, and the arm *g* is also provided with a slot or opening similar to the slot or opening *f*², and the corresponding end of the bar *e* passes therethrough, and the operation of the rotatable rod *e*³, as hereinafter described, moves the bar *e* forwardly and backwardly in the slots or openings *a*³, and the operation of the arm *f*, which is accomplished by the handle member *f*⁵ thereof, also rotates the rod *b*³. Mounted in the slots or openings *a*⁵ in the opposite end plates or mem-

bers *a*, said slots or openings being also substantially L-shaped in form, is a rod *h*, provided at its right-hand end, in the construction shown, and inside of the corresponding 5 end plate or member *a* with a collar *h*², to which is secured a chain or similar flexible device *h*³, one end of which is connected with the arm *c*⁴ of the collar *c* on the rotatable rod *b*³ and the other end of which is connected 10 with a spiral spring *h*⁴, which is secured to the arms *c*² of said collar, and the chain *h*³ or the front part thereof is carried forwardly and passed around a pulley or roller at *h*⁵, supported in the front end of the corresponding 15 part *a*⁴ of the corresponding end plate or member *a*, and the back part of said chain is passed around a roller or similar support at *h*⁶, connected with the corresponding end plate of member *a* below and rearwardly of 20 the rod *h*. Although the chain or other flexible device *h*³ is described above as consisting of one chain, it will be seen that it actually consists of two chains or similar devices, one of which is connected with the arm *c*⁴ and 25 with the collar *h*² and the other with said collar and the spring *h*⁴. The opposite end portion of the rod *h* is also provided with a collar *i*, similar to the collar *h*², and a chain *i*², composed of two parts, is connected with said 30 collar the same as the chain *h*³, one part of said chain *i*² being connected with a spiral spring *i*³, which is secured to the arm *d*² of the collar *d* on the rotatable shaft *b*³ and the other part of the chain *i*² being secured to 35 the arm *d*³ of the collar *d*, and the said chain *i*² or the parts thereof are passed around rollers or supports on the corresponding end plate or member *a* the same as the rollers or supports *h*⁵ and *h*⁶, around which the chain *h*³ or 40 the separate parts thereof are passed at the opposite ends of the frame, one of said rollers or supports—that which is connected with the corresponding part *a*⁴ of the left-hand end plate—being shown at *i*⁴ in Fig. 2, 45 and with this construction the movement of the arm *f* will move the bar *e* forwardly and backwardly in the slots or openings *a*³ and will move the rod *h* forwardly and backwardly in the slots or openings *a*⁵, and it will be observed 50 that when the rod *h* is in its rearmost position, as shown in Figs. 4 and 5, it is also in its lowest position, and the forward movement of this rod also raises it and shoves it forwardly into the position shown in Fig. 6. 55 Rigidly secured to the rod *h* and depending therefrom and spaced regularly thereon are candy spacers and markers *j*, which are substantially spoon-shaped in cross-section and which are preferably provided in the 60 lower end portions thereof and in the back thereof with small recesses *j*².

Mounted on the rod *h* and rotatable thereon is a candy-holder *k*, designed to hold the candies while the latter are being dipped in 65 the chocoate or other material, and this

candy-holder comprises a small rod *k*², connected with the rod *h* by hook members *k*³, a rod *k*⁴ parallel with the rod *k*², forwardly and backwardly directed segmental rods *k*⁵, which connect the rods *k*² and *k*⁴, and a rod *k*⁶, 70 connected with the forwardly and backwardly directed segmental rods *k*⁵ and formed into downwardly-directed yoke-shaped or loop-shaped members *k*⁷, and in the form of construction shown the hook members *k*³, 75 by means of which the candy-holder is connected with or made movable on the rod *h*, are also provided with L-shaped members *k*⁸, which are connected with the rods *k*² and *k*⁴, and the central hook member *k*³ is formed 80 into a downwardly and backwardly directed spring-arm *m*, which is adapted to engage the rod *e*³, as shown in Fig. 4, and hold the candy-holder in its closed position, as is also shown in Fig. 4, and the said candy-holder is 85 provided with a forwardly-directed handle member *m*², by which it may be raised or lowered or operated, as hereinafter described.

The end plates or members *a* of the dipping-frame are provided at the tops thereof 90 with outwardly-directed flanges or plates *a*⁷, which constitute handle members by means of which said frame may be manipulated, and the right-hand handle member *a*⁷ is provided with a forwardly-directed spring-arm 95 *a*⁸, provided at its end with a loop *a*⁹, adapted to receive the handle *f*⁵ of the arm *f* and hold said arm in its forward position.

In the use of my improved dipping-frame the arm *f* is moved forwardly, so as to project the bar *e*, with the needles *e*², forwardly, as shown in Fig. 4, and this operation also moves the rod *h* downwardly and backwardly, as shown in Fig. 4, in which position the candy spacers and markers *j* depend from 100 the bar *h* directly over the rear end portions of the needles or pins *e*², as shown in Fig. 4. In this position of the parts the candies are 105 placed on the needles or pins *e*² at regular intervals, one of said candies being indicated in 110 dotted lines at *m*³ in Fig. 4, and in this operation one candy is placed in front of each of the spacers and markers *j*, and after all the 115 candies have been placed on the needles or pins *e*² the holder *k* is turned down into the 120 position shown in Fig. 4, in which position the spring-arm *m* engages the rod *e*³ and secures 125 said holder in its closed position. The frame is then grasped by means of the handle members *a*⁷, and the bottom portion of 130 the frame is dipped into a tub or vat of liquid chocolate or similar material, so that the candies will be thoroughly covered with the chocolate or similar material. The frame is then lifted out of the chocolate, and the candy-holder *k* is raised by means of the handle *m*², and the frame is held in a slightly backward tilted position, so as to raise the 135 points of the needles or pins *e*², so that the candies will remain on said needles or pins,

and said frame is then agitated or shaken, so as to thoroughly distribute the chocolate over the candies, and this operation of shaking or agitating the frame may be accomplished manually, or it may be performed by any suitably-constructed machine, and this operation also removes all surplus chocolate both from the candies and the frame, and at the end of this operation the frame may be placed on a table or other support, and a narrow strip or board m^4 (indicated in dotted lines in Figs. 5 and 6 and also in Figs. 3 and 4) is placed under the needles or pins e^2 , and the arm f is swung backwardly into its rearmost position, and this operation moves the bar e backwardly into its rearmost position and drops the candies on the board m^4 , as indicated in dotted lines in Figs. 5 and 6, and the rod h by the same operation is raised and moved into its foremost position, as shown in Fig. 6, and in this operation an amount of surplus chocolate held by the spacers and markers j , and especially in the recesses j^2 thereof, is distributed over each of the candies, so as to make a mark thereon, as shown and described in the United States patent hereinbefore referred to, this mark consisting of a thickened raised strip or portion of chocolate extending across the body portion of the candies over or upon the regular coating of chocolate with which said candies are provided.

In the foregoing part of this specification I have described my improved dipping-frame only and one method of operating the same, and this dipping-frame constitutes the chief feature of this invention; but in Fig. 7 I have shown a casing, framework, or similar device n , in connection with which in practice my improved dipping-frame may be employed in the operation of removing the candies from the dipping-frame after the candies have been coated with chocolate, and the front part of said casing or frame is provided with a vertically-arranged endless chain n^2 , mounted on sprocket-wheels n^3 and provided at a predetermined point with a platform or support n^4 , upon which a number of boards m^4 are placed. The casing or framework n is provided at the top thereof with two arms o , but one of which is shown, and in practice after the dipping process hereinbefore described the dipping-frame is placed between and supported by the arms o , the handle members a^7 being moved backwardly onto said arms and held thereon by L-shaped fingers o^2 . The casing or frame n is provided with a plurality of drawers o^3 , any desired number of which may be employed, and said casing or frame is also provided with a tank o^4 , designed to contain ice, and said tank is located rearwardly of the arms o , and mounted in suitable bearings connected with said tank is a shaft o^5 , to which is secured an arm o^6 , which serves as a handle for operating said shaft, and the shaft o is also provided with a link member or members o^7 , to which is pivoted a supplemental link member or members o^8 , said supplemental link member or members o^8 being pivotally connected with a slide o^9 , movable on the casing or table m and on either side thereof, and the slide o^9 is also provided with a forwardly-directed member p , having a pivoted latch or latches p^2 , which are adapted to engage the top board m^4 when moved into its uppermost position by the movement of the chain n^2 . In practice after the dipping-frame has been placed on the arms o , as indicated in dotted lines in Fig. 7, the arm o^6 of the shaft o^5 is pulled forwardly, and this operation moves the top plate or board m^4 back into the position shown at m^5 in Fig. 7, at which time the board m^4 at m^5 is in position to receive the candies from the needles or pins n^2 , as hereinbefore described, and at this time the arm f of the dipping-frame is manipulated as hereinbefore described, so as to move the bar e backwardly and withdraw the needles or pins e^2 from beneath the candies and drop the latter on the board m^4 at m^5 , after which another board m^4 is moved up into position to be engaged by the latches p^2 , and another dipping-frame is placed in position and the arm o^6 again operated to move the top board m^4 into the position shown at m^5 , and the dipping-frame is again operated to drop the candies, and this operation may be repeated until the top drawer o^3 is entirely filled with candies, after which said top drawer is removed and placed in the position of one of the lower drawers, and said lower drawer is placed in the position of the top drawer, and this operation is continued until all the drawers of the casing or frame m are filled with candies.

From the foregoing description of the dipping-frame it will be seen that the end plates a and rods b and b^2 , by which they are connected, constitute a rigid frame for the movable parts of the device, and this rigid frame may be constructed in any desired manner, all that is necessary in this connection being that the end parts thereof be formed so as to permit the operation of the movable parts, as herein described. It will also be apparent that the bar e , which is movable forwardly and backwardly in the main stationary frame, together with the needles or pins e^2 , forms a support for the candies or the candy-cores in the operation of dipping and coating, and changes in and modifications of this feature may be made, all that is necessary being to provide a suitable open-work support which may be withdrawn from beneath the candies or candy-cores in the operation of dropping the said candies or candy-cores on the board or boards m , and the holder k may also be modified, all that is necessary in this connection being to provide a suitable rotatable holder composed of open-work and adapted to engage and hold the candy or candy-cores.

on the support, consisting of the parts *e* and *e*² in the form of construction shown, and various other changes in and modifications of the construction described may be made without departing from the spirit of my invention or sacrificing its advantages.

Having fully described my invention, what I claim as new, and desire to secure by Letters Patent, is—

- 10 1. A dipping-frame for coating candies or candy-cores provided with a horizontally-movable open-work candy-support, a rotatable open-work holder mounted thereover, and spacing and marking devices suspended from the support of the rotatable holder, substantially as shown and described.
- 15 2. A dipping-frame for coating candies or candy-cores provided with a horizontally-movable open-work candy-support, a rotatable open-work holder mounted thereover, spacing and marking devices suspended from the support of the rotatable holder, and means for moving said support upwardly and forwardly, substantially as shown and described.
- 20 3. A dipping-frame for coating candies or candy-cores, comprising rigidly-connected end members, a horizontally-movable open-work candy-support in the bottom portion thereof, a rod mounted longitudinally of said frame and provided with L-shaped guides in the end portions thereof whereby said rod may be moved upwardly and forwardly or backwardly and downwardly, a rotatable open-work candy-holder connected with said rod and spacing and marking devices suspended from said rod, substantially as shown and described.
- 25 4. A dipping-frame for coating candies or candy-cores, comprising rigidly-connected end members, a horizontally-movable open-work candy-support in the bottom portion thereof, a rod mounted longitudinally of said frame and provided with L-shaped guides in the ends thereof whereby said rod may be moved upwardly and forwardly or backwardly and downwardly, a rotatable open-work candy-holder connected with said rod and spacing and marking devices suspended from said rod, and means for operating said candy-support and said rod, substantially as shown and described.

- 50 5. A dipping-frame for coating candies or candy-cores comprising rigidly-connected end members provided with horizontal slots in the bottom portion thereof, an open-work candy-support movable in said slots, said end members being also provided with slots which range upwardly and forwardly or backwardly and downwardly, a rod mounted in said slots and adapted to move therein, an open-work candy-holder rotatably connected with said rod, spacing and marking devices suspended from said rod, and means for moving the open-work candy-support forwardly and backwardly and for operating said rod in

the slots in which it is mounted, substantially as shown and described.

6. A dipping-frame for coating candies or candy-cores, provided with a horizontally-movable candy-support, comprising a bar having forwardly-directed needles or pins, a rod mounted over said bar and movable upwardly and forwardly and backwardly and downwardly, an open-work candy-holder rotatably connected with said rod and spacers and markers rigidly connected with and suspended from said rod, substantially as shown and described.

7. A dipping-frame for coating candies or candy-cores, provided with a horizontally-movable candy-support, comprising a bar having forwardly-directed needles or pins, a rod mounted over said bar and movable upwardly and forwardly and backwardly and downwardly, an open-work candy-holder rotatably connected with said rod and spacers and markers rigidly connected with and suspended from said rod, and means for operating said candy-support and said rod comprising a rotatable shaft mounted longitudinally of the bottom portion of the frame, an arm connected with one end thereof and provided with angular slots in which the ends of said bar operate, another rotatable rod mounted in the top portion of said frame, means whereby the last-named rod may be operated by said arm, and devices connected with the last-named rod for moving the rod with which the candy-holder and candy spacers and markers are connected, substantially as shown and described.

8. A dipping-frame for coating candies or candy-cores, said frame being provided with end handles, a forwardly and backwardly movable open-work candy-support, a rotatable open-work candy-holder mounted over said support and movable upwardly and forwardly and backwardly and downwardly, and spacing and marking devices connected with the support of the open-work candy-holder and movable therewith, substantially as shown and described.

9. A dipping-frame designed for use in coating candies or candy-cores, said frame being provided with rigidly-connected end members, a horizontally-movable candy-support mounted in the bottom thereof and extending longitudinally thereof and provided with forwardly-directed needles or pins, a rod mounted longitudinally of the frame over the candy-support and movable upwardly and forwardly and backwardly and downwardly, an open wire-work candy-holder connected with said rod, and spacing and marking devices suspended from said rod, substantially as shown and described.

10. A dipping-frame designed for use in coating candies or candy-cores, said frame being provided with rigidly-connected end members, a horizontally-movable candy-sup-

port mounted in the bottom thereof and extending longitudinally thereof and provided with forwardly-directed needles or pins, a rod mounted longitudinally of the frame over the candy-support and movable upwardly and forwardly and backwardly and downwardly, an open wire-work candy-holder connected with said rod, and spacing and marking devices suspended from said rod, said spacing and marking devices being spoon-shaped in cross-section and provided in their lower back portions with recesses, substantially as shown and described.

11. A dipping-frame for use in coating candies or candy-cores provided with a horizontally-movable candy-support, comprising parallel needles or pins, an open-work candy-holder mounted thereover and movable upwardly and forwardly or backwardly and downwardly, and candy spacing and marking devices suspended from the support of the rotatable candy-holder, substantially as shown and described.

12. In a dipping-frame for coating candies or candy-cores, a horizontally-movable open-work candy-support mounted in the bottom portion of said frame, a rod mounted in the end portions of said frame and extending longitudinally thereof over the candy-support and movable in L-shaped guides formed in the ends of said frame, a rotatable rod mounted in the top back portion of said frame and provided with end arms, chains connected with said arms and with the opposite ends of said first-named rod, said chains being passed around roller-guides arranged forwardly and backwardly of the opposite ends of said first-

named rod, means for operating the rotatable rod, a rotatable open-work candy-holder connected with the first-named rod and 40 candy spacers and markers suspended from said first-named rod, substantially as shown and described.

13. A dipping-frame for coating candies or candy-cores, provided with a longitudinally-arranged and forwardly and backwardly movable candy-support, and spacing and marking devices suspended over said support longitudinally thereof, substantially as shown and described. 50

14. A dipping-frame for coating candies or candy-cores, provided with a longitudinally-arranged open-work candy-support, means for moving said support forwardly and backwardly, and means for holding candies on 55 said support while the latter is being agitated, substantially as shown and described.

15. A dipping-frame for coating candies or candy-cores, said frame being provided with a forwardly and backwardly movable open-work candy-support, spacing and marking devices arranged thereover and means for holding the candies on said support, while the latter is being agitated, substantially as shown and described. 60 65

In testimony that I claim the foregoing as my invention I have signed my name, in presence of the subscribing witnesses, this 4th day of May, 1905.

PANAYIOTIS PANOULIAS.
